H. W. PLEISTER

METHOD FOR METAL COATING

Filed Dec. 29, 1923

Inventor:
Henry W. Pleister,

By his attorney,
Harold D. Penney

UNITED STATES PATENT OFFICE.

HENRY W. PLEISTER, OF WESTFIELD, NEW JERSEY, ASSIGNOR, BY MESNE ASSIGNMENTS, TO DIAMOND EXPANSION BOLT COMPANY, OF NEW YORK, N. Y., A CORPORATION OF NEW YORK.

METHOD FOR METAL COATING.

Application filed December 29, 1923. Serial No. 683,424.

To all whom it may concern:

Be it known that I, HENRY W. PLEISTER, a citizen of the United States, and resident of Westfield, in the county of Union and State of New Jersey, have invented certain new and useful Improvements in Methods for Metal Coating, of which the following is a specification.

This invention relates to the method of coating iron or steel articles with zinc applied in a molten state and allowed to cool and harden thereon, the process commonly known as galvanizing.

This invention relates more particularly to the process of distributing the liquid or semi-liquid coating of zinc while still in a molten state on the surface of the articles so as to form a smooth and even coating of equal density on all surfaces of an irregularly shaped article.

Another object of this invention is to prevent the articles remaining in close contact one with the other when handled in a mass in order to prevent their sticking or freezing one to the other.

It is customary in the process of galvanizing after an article or a mass of articles have been properly pickled to immerse the article separately or a mass of articles in perforated baskets into a bath of molten zinc approximately 50 degrees to 100 degrees Fahrenheit above the melting point of the zinc and to allow the articles to remain until raised to a temperature equal approximately to the heat of the molten zinc; the articles are then subjected to various treatments after they are taken out of the bath according to the different processes employed by various galvanizers such for instance as shaking the basket vigorously by hand and throwing the contents on the floor to spread the articles and to prevent stickers, wiping the surface to spread the coating smoothly and to remove excess spelter or subjecting the mass to rotation so that the excess spelter is thrown off by centrifugal force.

The objectionable features to all of these processes are numerous, the cost of wiping threads on bolts is excessive and the result does not bring about a smooth and uniform job. Such bolts often require the threads to be re-cut with a die in order to permit the nuts being turned on the bolts. The shak-

ing in perforated baskets by hand is excessively laborious and the production per man is very low. Submitting the articles to simple centrifugal motion has its disadvantages in that the mass thus rotated retains its original relative position one article to the other in the centrifugal chamber. Thus articles for instance which happen to be at the center of the centrifuge will continue there to remain and to cast excess spelter on the articles nearer the periphery which excess spelter often freezes on the articles at the outside or periphery causing blisters, icicles, roughness and excess spelter. Articles treated in this manner retaining their same relative position one to the other will in many cases freeze or stick together when the zinc cools and hardens and when broken apart will leave bare or exposed spots on one or the other. When a simple centrifuge is used the articles will be coated more thickly on the side further removed from the center than on the side nearer to the center. This is for the reason that the article retains its original position and the centrifugal force will draw the fluid spelter outwardly taking it from the side nearer the center and drawing it to the side further away causing an uneven distribution of the zinc when hardened. Another objection to the simple centrifuge is that in a mass of articles the articles nearer or at the periphery are subject to more violent action than those nearer to or at the center where practically no action occurs. This it will be readily seen causes different densities of coating to be left on the articles. With sufficient speed it is possible practically to cast off all the spelter from the outer articles while those at the center of rotation still retain a very thick coating.

In my process of galvanizing I employ a primary horizontal rotary platform upon which is mounted between its center and circumference a secondary rotating platform. Upon this is mounted suitable supports for retaining a perforated basket. A planetary rotation of the secondary rotating platform is obtained by means of a fixed pinion at the center of the primary rotating platform which pinion meshes in the teeth of a gear mounted underneath the secondary platform on its center. Thus when the primary platform is rotated the pinion being fixed

against rotation the secondary platform will rotate in relation to the primary platform causing a compound rotary movement, one movement being about the center of the primary rotating platform and the other movement about its own center which is located outside the center of the primary platform.

This process need not be limited to any particular design of apparatus so long as 10 the centrifugal action upon the articles will be carried out in a manner which will be described and claimed as new hereafter. In order to make this application entirely clear I will describe it in connection with the particular preferred apparatus that is shown in 15 the drawings.

It is further understood that the speed of revolution of the secondary centrifuge may be varied in relation to the primary to any 20 degree that is found more efficient for certain classes of work. While in the majority of cases the relation of three revolutions to the primary rotating platform to one revolution of the secondary rotating 25 platform is found to be most satisfactory this relation may easily be changed by the substitution of different sizes of gears and pinions. For ease of description I will in the accompanying drawings and following description illustrate and describe the action 30 of the apparatus so constructed as to give one revolution on the primary to one revolution on the secondary rotating platform.

Figure 1 is a cross sectional elevation of 35 the preferred form of my apparatus; and

Figure 2 is a horizontal view of same, looking down upon the rotatable platforms;

Figures 3, 4, 5, and 6 are diagrammatic plan views of the rotatable platforms in different positions taken at each quarter turn, 40 each platform rotating clockwise; and

Figs. 7 and 8 are diagrammatic plans showing orbits of an article; with different ratios between the rotation of the primary and secondary tables.

In Figures 1 and 2 *a* is a stationary pinion mounted rigidly on a fixed shaft *b* supported on a base *c*; the primary rotatable platform *d* is loosely fitted to the shaft or column *b*. 50 This rotatable table may be actuated by a belt about the pulley *e* or by shaft and gear or in any other suitable manner. A secondary rotatable platform *f* is mounted on a shaft *g* spaced between the center of the primary table and its circumference and fixed rigidly to a gear wheel *h* which meshes with the pinion *a*. On the secondary rotatable platform *f* is suitably mounted a perforated basket *j* supported by upright *k*. When the 55 primary platform *d* is rotated the secondary platform will travel with it about the center of the column *b* at the same time rotating about its own center. This apparatus is 60 preferably enclosed in a steel or other suitable shield *l* to prevent the spelter which is

cast off the coated article from flying about the room and to allow it to fall to the bottom of the enclosure where it may be removed and replaced in the molten bath for repeated use.

In my process of galvanizing articles to be coated are first cleaned or pickled in the usual manner in diluted sulphuric, hydrofluoric or muriatic acid, according to the class of work, different acids being used for 70 bright cold rolled steel, rough hot rolled steel, cast iron, etc. After being pickled they are immersed in a bath of molten zinc at approximately 850 to 900 degrees Fahrenheit larger articles being immersed separately or strung on wires, smaller articles being immersed in a mass in a perforated steel basket. The articles are allowed to remain in the zinc bath until they have attained approximately the temperature of the bath 75 throughout. They are then taken from the bath and placed upon the secondary rotary table *f* of my apparatus and subjected while the zinc coating is still in a liquid or semi-liquid state on the surface of the articles to 80 a compound rotary motion sufficiently long to expel all surplus zinc and evenly to distribute the coating of molten zinc smoothly and of equal density over the entire surface of the articles. Very few revolutions of the 85 apparatus are necessary to accomplish this and the material is then removed from the apparatus. If small articles are treated in bulk in a perforated basket the basket is 90 taken from the machine and dumped upon an inclined chute, while sliding down this chute they are sprinkled with salammoniac and allowed to fall into a tank of clear cold water. This process results in a smooth 95 bright coating of zinc upon the steel or iron articles with uniform thickness on all surfaces free from lumps, projections, blisters or any kind of roughness. Where threaded articles are so coated the threads of a bolt are clear and free in the threads and in the 100 slot of the head so that no further cleaning or machine work is necessary on them and a nut may be run freely over the threads of the bolts.

The even distribution of the metal on the 105 articles is accomplished by the particular rotary motion which is applied in my apparatus and which motion is illustrated in Figures 3, 4, 5, 6 and 7. In Figure 3, I have shown as exemplary of many other shapes an 110 article *M* having at least four sides *N*, *R*, *O*, *P*, placed in a perforated basket upon the secondary rotating platform *f*. Its position in the basket is one of any number of 115 positions that it may have when the basket is 120 removed from the molten zinc and is one of many similar articles with which the basket is filled though not shown in the drawing. Its position will be retained approximately 125 as it is placed in the basket due to its con- 130

tact with the surrounding articles which fill the basket. In Figure 3 and each of the succeeding Figures 4, 5, and 6, the lines of centrifugal force radiate from the center X of the primary rotatable table and are marked LCF. When the primary rotatable table is turned clockwise the secondary table will also turn clockwise and in an orbit around the center X. When in the position shown in Figure 3 the lines of centrifugal force will draw the liquid metal from the side P to the side R. When the primary rotatable table has made a quarter turn on its center Figure 4, the secondary rotatable table will have made a quarter turn on its center also, and the article M will take the position shown in Figure 4 and the lines of centrifugal force are from the sides O and P toward the sides R and N. When the next quarter turn has been made Figure 5, the article M has taken the position shown in the drawing and the lines of centrifugal force are from the side R toward the side P. When the next quarter turn has been taken the article M is in the position shown in Figure 6 and the lines of centrifugal force are from the sides N and P toward the sides R and O. When the next quarter turn has been taken the article M will have again taken the position shown in Figure 3, the original position at which it started, and the lines of centrifugal force will be from the side P to the side R. Thus it will be seen that the centrifugal action upon the article M is constantly changing in its direction causing the metal to be drawn on its surfaces in ever changing directions assuring the casting off of surplus metal from every angle on the surface and assuring a smooth and uniform distribution of the fluid metal over the entire surface of the article.

From the above description it can readily be seen that the ever changing direction of the lines of centrifugal force upon the article treated produces an entirely different action from that obtained in the simple centrifuge where the direction of the lines of centrifugal force remain constant at all times on each article and where the articles at the inner portion of the centrifuge are continually expelling metal upon those located at the outer portion or nearer to the periphery of the centrifuge. In my process the article treated is not allowed to remain at the same distance from the center at any time but is constantly changing its location from the center of the primary rotatable table. In Figure 3, the article M is shown at its extreme distance from the center X. In Figure 4 it is shown at a point between the extreme and the minimum distance from the center X. In Figure 5 it is shown at its minimum distance from the center X. In Figure 6 it is again shown at a point between the extreme and the minimum distance from the center X and again in Figure 3 it is shown at the point of beginning the extreme distance from the center X. In Figure 7, I have shown by means of line S the orbit or path of the article M in its rotation about center X where the number of revolutions of the primary and secondary rotatable tables are the same. In Figure 8, I have shown the orbit of the article M about the center X where the primary table makes three revolutions to one revolution of the secondary table. As stated before in this description where a simple centrifuge is used certain articles at or adjacent to the center receive little or no centrifugal action while those at or adjacent to the circumference are more forcibly affected by the centrifugal action. With my process all articles receive practically equal centrifugal treatment in their passage from maximum to minimum distance from the center.

While I have stated above the articles will be held in the same relative position one to the other during the process of expelling the excess spelter during their treatment in my apparatus, there is still sufficient agitation among the articles caused by the changes in lines of centrifugal force exerted upon them to prevent their adhering one to the other so that when the rotation has been completed and the articles are dumped from the basket down the inclined chute into the water they will be comparatively free from stickers, the term usually applied to galvanized articles which adhere one to the other.

Articles M disposed over the teeth the wheel h will vary in speed substantially from zero speed to high speed. Articles nearer the axis of the wheel h will vary in speed less.

It is further to be understood that while I have shown both the primary and secondary rotatable tables operated in a clockwise direction I may obtain a similar result by rotating one in a clockwise and the other in a counterclockwise direction by the insertion of another gear wheel or in other ways. It is particularly noted that the invention is not limited to the details and metal described as these may be greatly varied without departing from the scope of the invention as claimed.

I claim as my invention:

1. A process comprising applying molten metal to an article; then subjecting the article to motion in an endless deeply curved path; and at the same time varying the relation of the article with respect to the path.
2. A process comprising applying molten metal to articles; then subjecting the articles to motion in an endless deeply curved path; and at the same time varying the speed of the articles.
3. A process comprising applying molten metal to articles; then subjecting the articles

- to motion in an endless deeply curved path at sufficient speed to throw metal from the articles; and at the same time varying the speed of the articles.
5. A process comprising applying molten metal to articles; then subjecting the articles to motion in an endless deeply curved path; and at the same time varying the curvature of the path.
10. 5. A process comprising applying molten metal to articles; then subjecting the articles to cyclic motion in a curved path; and at the same time varying the relation of the articles with respect to the path.
15. 6. A process comprising applying molten metal to articles; then subjecting the articles to cyclic motion in a curved path; and at the same time varying the speed of the articles.
20. 7. A process comprising applying molten metal to articles; then subjecting the articles to cyclic motion in a curved path; and at the same time varying the curvature of the path.
25. 8. A process comprising applying molten metal to articles; then subjecting the articles to cyclic motion in a curved path; and at the same time varying the angle of the articles with respect to the path.
30. 9. A process comprising applying molten metal to an article; then subjecting the article to planetary motion.
35. 10. A process comprising applying molten metal to an article; then subjecting the article to centrifugal force; and at the same time varying the relation of the force with respect to the article.
40. 11. A process comprising applying molten metal to articles; then subjecting the articles to centrifugal force; and at the same time varying the angle of the force with respect to the articles.
45. 12. A process comprising applying molten metal to articles; then subjecting the articles to cyclic centrifugal force; and at the same time varying the angle of the force with respect to the articles.
50. 13. A process comprising applying molten metal to articles; then subjecting the articles to cyclic centrifugal force; and at the same time varying the relation of the force with respect to the articles.
55. 14. A process comprising applying molten metal to an article; then subjecting a carrier with the article therein to motion in an endless deeply curved path; and at the same time varying the angle of the carrier with respect to the path.
60. 15. A process comprising applying molten metal to articles; then subjecting a carrier with articles therein to motion in an endless deeply curved path; and at the same time positively varying the angle of the carrier with respect to the path.
65. 16. The process of galvanizing which consists in immersing the articles in molten zinc, then removing them and subjecting them to a rotary motion while the zinc is still in a liquid or semi-liquid state on the surface of the articles in which motion the articles are rotated centrifugally in constantly changing distances from the center of the centrifuge.
70. 17. The process of galvanizing which consists in immersing the articles in molten zinc, then removing them and subjecting them to a rotary motion while the zinc is still in a liquid or semi-liquid state on the surface of the articles in which motion the articles are rotated centrifugally in constantly changing distances from the center of the centrifuge whereby each article is subjected to the same amount of centrifugal force as the others.
75. 18. The process of galvanizing which consists in immersing the articles in molten zinc, then removing them and subjecting them to a rotary motion while the zinc is still in a liquid or semi-liquid state on the surface of the articles in which motion the articles are constantly and alternately drawn toward the center and away from the center of the centrifuge.
80. 19. The process of galvanizing metal articles consisting of immersing them in a bath of molten zinc until the temperature of the articles has been brought up to approximately the temperature of the zinc, then subjecting the articles in a mass while the zinc is still in a liquid or semi-liquid state on the surface of the articles to a compound rotary motion in which motion the position of the articles in relation to the lines of centrifugal force is continuously changed.
85. 100. 20. The process of galvanizing metal articles consisting of immersing them in a bath of molten zinc until the temperature of the articles has been brought up to approximately the temperature of the zinc, then subjecting the articles in a mass while the zinc is still in a liquid or semi-liquid state on the surface of the articles to a compound rotary motion in which motion the position of the articles in relation to the lines of centrifugal force is continuously changed 105
110. 115. 21. The process of galvanizing metal articles consisting of immersing them in a bath of molten zinc until the temperature of the articles has been brought up to approximately the temperature of the zinc, then subjecting the articles in a mass while the zinc is still in a liquid or semi-liquid state on the surface of the articles to a compound rotary motion in which motion the position of the articles in relation to the lines of centrifugal force is continuously changed 110
120. 125. 22. The process of galvanizing metal articles consisting of immersing them in a bath of molten zinc until the temperature of the articles has been brought up to approximately the temperature of the zinc, then subjecting the articles in a mass while the zinc is still in a liquid or semi-liquid state on the surface of the articles to a compound rotary motion in which motion the position of the articles in relation to the lines of centrifugal force is continuously changed 120
130. 135. 23. The process of galvanizing metal articles consisting of immersing them in a bath of molten zinc until the temperature of the articles has been brought up to approximately the temperature of the zinc, then subjecting the articles in a mass while the zinc is still in a liquid or semi-liquid state on the surface of the articles to a compound rotary motion in which motion the position of the articles in relation to the lines of centrifugal force is continuously changed 130

the excess spelter will be cast off in ever changing directions relative to the position of the article.

22. The process of galvanizing metal articles consisting of immersing them in a bath of molten zinc until the temperature of the articles has been brought up to approximately the temperature of the zinc, then subjecting the articles in a mass while still at approximately the same temperature and while the zinc is still in a liquid or semi-liquid state on the surface of the articles to a compound rotary motion in which motion the radial position of the articles in relation

15 each to the other is continually changed.

23. The process of galvanizing metal articles consisting of immersing them in a bath of molten zinc until the temperature of the articles has been brought up to approximately the temperature of the zinc, then subjecting the articles in a mass while still at approximately the same temperature and while the zinc is still in a liquid or semi-liquid state on the surface of the articles to a compound rotary motion in which motion

25 the distance of each article from the center of the centrifuge is continually changed from periphery to center and from center

to periphery passing through all points intermediate thereto.

30

24. The process of galvanizing metal articles consisting of immersing them in a bath of molten zinc until the temperature of the articles has been brought up to approximately the temperature of the zinc, 35 then subjecting the articles in a mass while still at approximately the same temperature and while the zinc is still in a liquid or semi-liquid state on the surface of the articles to a compound rotary motion in which motion 40 the distance of each article from the center of the centrifuge is continually changed from periphery to center and from center to periphery passing through all points intermediate thereto, whereby no article will be 45 allowed to remain at the circumference to receive the cast off spelter from articles nearer the center thereby insuring articles which are initially placed at the circumference receiving the same treatment as those 50 initially placed at or nearer the center.

Signed at New York, in the county of New York and State of New York, this 26th day of Dec., A. D. 1923.

HENRY W. PLEISTER.
